UNITED STATES PATENT OFFICE.

LUIS MAYOLINO, OF HABANA, CUBA.

WAVE-MOTOR.

1,140,521.

Specification of Letters Patent. Patented May 25, 1915.

Application filed November 13, 1913. Serial No. 800,785.

To all whom it may concern:

Be it known that I, LUIS MAYOLINO, a citizen of the Republic of Cuba, residing at Havana, Cuba, have invented new and useful 5 Improvements in Wave-Motors, of which the following is a specification.

The invention relates to a wave motor.

An object of the invention is to provide a device wherein a piston is reciprocated by 10 the waves of a body of water and wherein the movement of the piston is transmitted to a pump or to another machine for utilizing the energy of the waves.

Another object of the invention is to provide in a device of this kind a piston with 15 means for maintaining the same constantly in contact with or partly immersed in a body of water even if the level of said body is subjected to fluctuations within wide limits.

20 Another object of the invention is to provide a device of this kind with means for automatically regulating the movement of the piston in accordance with the force of the waves or in accordance with the tidal fluctuations.

25 With these and other objects in view I have illustrated an embodiment of the invention in the accompanying drawing and reference will be made to this drawing in 30 the following specification, the novel features being more clearly pointed out in the appended claims.

In the drawing: Figure 1 is a vertical section through an installation of this kind, the 35 machine to be driven by the force of the waves being not shown in this figure. Fig. 2 is a horizontal section through the tunnel connecting a well, in which a piston operates, with a body of water, the section being 40 taken on the line 2—2 of Fig. 1. Fig. 3 is a vertical section through the well in which the piston operates shown in connection with a pump driven by said piston, various parts in this figure being shown in elevation.

45 A well excavated from the soil near a body of water is indicated at 1, and the rigidity of the walls of this vertical well is enhanced by the lining 3 of concrete or similar suitable material applied to the walls of the 50 well. The interior of this well is in communication with the body of water 2 by means of a tunnel 4, the bottom of which is somewhat inclined to facilitate the inflow of the water toward the foot of the well. The tunnel 55 preferably has elliptic cross-section and

tapers from the inlet toward the well as may be seen from Fig. 2, the two axes of the ellipse at the end of the tunnel near the well being preferably equal to the diameter of the well so that the cross-section gradually 60 assumes a circular shape. It is advisable to apply a coating or lining of concrete to this tunnel to decrease the friction of the water on the walls thereof. At the inlet end of the tunnel the longest axis of the ellipse is about 65 twice the diameter of the well, while the shorter or vertical axis is approximately equal to the diameter of the well. The slope of the bottom of the tunnel toward the well prevents the tunnel's being completely emp- 70 tyed when the tide ebbs.

The depth of the well 1 may vary. This dimension probably will depend upon the geological conditions of the shore and also upon the power or energy that is to be trans- 75 mitted from the waves.

A piston 5 is slidably disposed within the well 1 conforming in its outline to the configuration of the wall of the well 1, so as to be movable therein. In order to improve the 80 guiding of the reciprocating piston a plurality of guiding elements 10 may be located within the well and these elements must be long enough to have a guiding effect upon the piston even if the same reaches its up- 85 permost or lowermost position.

The piston comprises two chambers which are separated from each other by means of a partition wall A. The lower chamber 7 will be designated in the following as a water chamber, while the upper chamber 6 serves as an air chamber, this air chamber being closed on top and the water chamber being open at the bottom. The location of the partition wall A between 90 the two chambers may vary in accordance with the weight of the piston and in accordance with the power which is to be transmitted therethrough. The water chamber may be placed in communication 95 with the atmosphere by means of the pipe 8 which extends from the chamber 7 through the air chamber 6, the lower end of this pipe being open and the upper one being closable by means of a valve 35. The air chamber 6 which is closed at the bottom and at the top may also be brought into communication with the atmosphere by means of the pipe 9 which extends from 100 near the bottom of the chamber 6 through 105

the top of the same and which also may be closed at the outstanding end by means of a valve 36.

When water enters into the lower chamber, atmospheric connection through pipe 8 is established so that all the air contained in the lower chamber is forced out by the incoming water and a complete filling of the water chamber takes place. Thereupon

10 the atmospheric connection is cut off by closing the valve 35 and the lower chamber is permanently filled with water. Due to this fact the piston is adapted to simultaneously follow any movement of the water 15 whereby a high degree of efficiency of the device is effected. The upper chamber 9 is provided to obtain a high degree of buoyancy for the piston. The pipe 9 which connects the upper chamber with the atmosphere is not an essential feature of the device and may be dispensed with. It merely permits the removal of the air from the upper chamber by mechanical means should this be deemed necessary.

25 Any suitable machine may be driven by the waves in co-action with the piston. In the embodiment illustrated a double acting pump is shown secured to the frame 11 which is supported on beams 41 bridging the mouth of the well. The cylinder 12 of this pump is relatively long and the piston rod in said cylinder is connected with the rod of the piston 5 in the well so that the pump piston has a stroke of exactly the 30 same length as the power piston. The pump piston 13 is secured to the piston rod 12' of the pump and is surrounded by several packing rings which may be expanded to compensate for wear of the piston. A 35 connection of the two piston rods is effected by means of the clutch collar 15 which is secured to the hub of the piston 5 by means of the wedge or key 16.

Two pipes are in communication with the 40 cylinder of the pump, one at each side thereof. One of these pipes as indicated at 17 serves for drawing the water by suction into the cylinder and a flanged opening 18 in this pipe is therefore connected by means 45 of another pipe (not shown) with the water supply. A plurality of regulating valves 50 22 are located in this suction branch of the pump and check valves 21 serve for preventing the water from flowing from the 55 pump in direction toward said valves 22.

The compression side of the pump as indicated at 19 is equipped similarly and comprises a discharge opening 20 located about mid-way in the discharge side and several 60 regulating valves 23 and check valves 22'.

From the above it will be seen that during each stroke of the pump a suction is exerted in the pipe 17 and the water is conveyed by means of the pump toward the 65 compression side 19 from where it is dis-

charged. Safety valves 24' may be located on top and on bottom of the pump cylinder and may be adjusted so as to relieve automatically any excessive pressure in the pump. The relation between the diameter 70 of the power piston 5 and the pump piston 13 depends upon the volume of water to be conveyed by the pump.

Means are provided for regulating automatically the inflow of water to the well in accordance with the height of the waves. For this purpose another cylindrical well 24 is sunk from the level of the shore to the tunnel 4 which connects the body of water 2 with the well 1. The diameter of this second well 24 is considerably smaller than that of the power well 1 and may be only one third of the same. The piston 25 is movable in this auxiliary well and controls in its movement the position of a gate 26 adapted to shut off or open the tunnel leading to the well 1. The gate is slidably held in guides 27 which extend vertically down to the tunnel and the piston rod 28 of the piston 25 is connected with the rod 29 mounted on the 90 gate by means of links 30 and 31 and a beam 32. This beam is pivotally mounted on the standard 34 as indicated at 33. When the force of the waves becomes excessive the piston 25 is forced upwardly and lowers 95 thereby the gate 26 so that the access of the waves to the power well 1 is partially restricted.

The operation of the device is as follows: Incoming waves continue their movement 100 through the submarine tunnel 4 and impelling against the piston 5 in the well 1 they raise said piston whereby also the pump piston 13 is forced upwardly. The movement of the pump piston will produce 105 a partial vacuum in the chamber of the pump below said piston and water is drawn in by suction through pipe 17 and check valve 21 into said chamber. The movement of the piston in upward direction within the 110 cylinder of the pump forces the water in the chamber above the piston toward the compression side of the pump and thence through the pipe 20 into some conduit (not shown) from where the water is led to the 115 locality where it is to be utilized. The receding wave will have the effect that the piston 5 in the well 1 simultaneously follows the receding water level and the power piston, therefore, is lowered together with the 120 pump piston 13. A vacuum is produced in the chamber above the pump piston 13 and the water is drawn in by suction through the pipe 18 into this chamber. The downward movement of the piston forces the water in 125 the pump cylinder in the chamber below the piston toward the compression side from where it is discharged into a conduit.

I claim:

1. A wave motor comprising a well ex- 130

- cavated in proximity to the shore of a body of water, a piston movable in said well, a pump, means connecting said piston with the pump, a tunnel connecting the lower end 5 of the well with the body of water and means controlled by the water passing through said tunnel for regulating the amount of water entering the well.
2. A wave motor comprising in combination with a well excavated in proximity to the shore of a body of water, a piston slidably movable in said well, a machine operatively connected with said piston, a tunnel connecting the lower end of said well with 10 the body of water and means controlled by the water flowing through said tunnel for regulating automatically the amount of water entering the well.
3. A wave motor comprising in combination with a well excavated in proximity to the shore of a body of water, a piston slidably movable in said well, a machine driven by said piston, a tunnel connecting the lower end of said well with the body of water, a 15 gate guided in said tunnel and means con-

trolled by the water flowing through the tunnel for raising and lowering said gate to regulate the amount of water entering the well.

4. A wave motor comprising in combination with a well excavated in proximity to the shore of a body of water, a piston slidably movable within said well, a machine driven by the movement of said piston, a tunnel connecting the lower end of the well with said body of water, a second well communicating with said tunnel, a piston movable in said second well, said second well being excavated closer to the body of water than the first named well, a gate movable 30 through said tunnel and means connecting said second piston with said gate for displacing the latter vertically with respect to the tunnel.

In testimony whereof I affix my signature 35 in presence of two witnesses.

LUIS MAYOLINO.
